UNITED STATES PATENT OFFICE.

HENRY GOLDBERGER AND MORRIS GOLDBERGER, OF CHICAGO, ILLINOIS.

SURFACING DEVICE FOR TRACING-CLOTH.

1,211,932.

Specification of Letters Patent.

Patented Jan. 9, 1917.

Application filed November 27, 1914. Serial No. 874,187.

To all whom it may concern:

Be it known that we, HENRY GOLDBERGER and MORRIS GOLDBERGER, citizens of the United States, and residents of Chicago, in the county of Cook and State of Illinois, have invented certain new and useful Improvements in Surfacing Devices for Tracing-Cloth; and we do hereby declare that the following is a full, clear, and exact description thereof, reference being had to the accompanying drawings, and to the characters of reference marked thereon, which form a part of this specification.

This invention relates to a novel device for use by draftsmen for preparing the surface of tracing cloth to receive ink, which preparation consists of the application to the surface of the cloth of a powder such as prepared chalk and the like in a manner to smooth the surface of the cloth and to clean it of grease and moisture clinging thereto and thus prepare the surface to readily receive the ink.

The purpose of the invention is to provide in a single unitary device a holder or receptacle for the powder having a closable opening or openings through which the powder may be sifted on the tracing cloth and formed also to constitute a hand piece provided at one side with a yielding flat pad, such as felt or like abrasive material, which is adapted to be rubbed over a layer of powder sprinkled on the cloth to prepare the surface to receive the ink.

Heretofore it has been a common practice in applying such powder to the tracing cloth to rub the powder over and into the surface of the cloth by the heel of the hand, a rag or the like. A practical objection to this mode of applying the powder to the cloth is that the powder is not uniformly spread over or applied to the surface thereof, leaving portions of the glazed surface unprepared. For this reason the ink lines take better in some parts of the prepared surface than others, whereby said ink lines become irregular. Our improved device overcomes this defect in the application of the powder to the cloth and also provides a device by which the treating of the surface of the cloth in the manner described is facilitated and the time required therefor is shortened as compared with prior practice.

We have shown in the drawings a preferred embodiment of our invention, but it will be understood that the invention is

capable of embodiment in other specific forms, and the invention is not limited, therefore, to the structure shown in the drawings, except as hereinafter specifically claimed, and as imposed by the prior art.

In the drawings, Figure 1 is a side elevation of a tracing cloth surfacing device embodying our invention, with parts broken away. Fig. 2 is an end elevation thereof. Fig. 3 is a partial section on the line 3-3 of Fig. 2. Fig. 4 is a similar section, showing the device in position to sift the surfacing powder on the cloth.

As shown in the drawings, 10 designates the holder, as a whole. It is hollow and is shaped to constitute an elongated hollow receptacle for the powder. Conveniently, it may assume the general form and proportions of a black-board eraser, the top of the holder body being centrally depressed and the side edges of the top portion being rounded or ribbed so as to enable the device to be readily grasped by the hand of the user. The holder is shown as made of wood, but may be made of any other suitable material. The lower side of the frame is provided with a rubbing layer or facing member 12, which may be made of felt or like abrasive, relatively compact rubbing material and may be cemented to the holder body, and said layer has a flat lower surface.

Extending across one open end of the holder 11 is a plate 14 which is attached to the end of the holder body in any suitable manner, as by the nails 15. The said plate 14 is provided with a plurality of apertures 16 which constitute openings through which the powder may be sifted upon the cloth to be treated. The said apertures are adapted to be normally closed by a closure plate 17 applied over and fitted flat upon the plate 14. The closure plate is provided with a plurality of apertures 18 that are adapted, by relative movement of the plates 17 and 14, to be brought into register with the apertures 16 of the plate 14 so that in one position thereof the powder may be sifted through the end plates, and in another position the imperforate parts of the outer plate 17 close the apertures 16. The relative movement to bring the said apertures into and out of register may be of any preferred kind. As herein shown, it is a sliding movement which may be effected by providing the plate 17 with slots 20 through which ex-

tend guide pins 21, 21 that are fastened in any suitable manner to the holder.

The closure plate may be held in place to cover the apertures 16 of the inner plate 14 by means of a spring 22 which surrounds a stud 23 that is formed on or is carried by the lower edge of the sliding plate 17; said spring being interposed between a shoulder 24 on the said stud and an outwardly turned 10 lip or flange 25 formed on or carried by the lower edge of the fixed plate 14. As herein shown and preferably, the end plate 14 and the closure plate 17 are made entirely of sheet metal by a suitable swaging operation.

15 The closure plate is adapted to be depressed by means of a thumb piece 26 which is formed on or is carried by the upper edge thereof and is preferably turned backwardly over the upper side of the holder so as to be within easy access of the thumb of the user of the device when grasping the holder in a natural manner to operate the same. In order that the shiftable closure plate may be arrested in position to bring the apertures thereof in complete register, suitable interacting stops are provided on said plates which may consist of the contact of the lower margin of the closure plate with the lip 25 of the fixed plate.

20 30 The end of the holder, opposite to the shiftable closure, is provided with a cover plate 27 which may be movable or removably connected to the holder in any suitable manner so that when removed or shifted the holder or receptacle may be charged and when in place serves to prevent the escape of powder.

35 In using the device the holder is grasped in much the same manner as a crayon eraser 40 for black-board use. In order to release the powder from the holder the thumb is pressed downwardly upon the thumb piece 26 to shift the closure plate to bring the apertures thereof into register with those of the plate

14, whereupon the powder may be sifted on 45 the tracing cloth in the manner indicated in Fig. 4. Thereafter the thumb is released from the thumb piece to allow the spring to restore the closure plate. Thereafter, and without changing the position of the holder 50 in the hand, the powder is spread over the tracing cloth by rubbing the pad member 12 flat over the powder and cloth. By reason of the fact that the said cushion or pad is flat and, therefore, parallel to the cloth and is 55 of substantial area and is relatively solid, the powder is applied uniformly to the surface of the cloth so that ink lines thereafter applied to said surface will be uniform throughout.

60 We claim as our invention:—

In a holder for an abrading and filling implement for tracing cloth the combination with a hollow body having a flat underface and a concaved upper handle portion, 65 a pad secured to said underface, a perforated plate secured to and closing the end of said body, and terminating at its lower end in a forwardly projecting perforated lip, a second perforated plate slidably 70 mounted on the first named perforated plate, a stud depending from the slidably mounted plate, and projecting through the perforation on said lip, a coiled spring around the said stud and resting upon said 75 lip, an operating handle extending inwardly from the top of the slideable plate and positioned over the holder within the concave upper portion of the handle.

In testimony that we claim the foregoing 80 as our invention we affix our signatures in the presence of two witnesses, this 21st day of November, A. D. 1914.

HENRY GOLDBERGER.
MORRIS GOLDBERGER.
